GROUND PLATE AND CONNECTOR

Frederick H. Luecke, Boulder, Colo.

Application December 16, 1948, Serial No. 65,612

2 Claims. (Cl. 174—6)

1

This invention relates to grounds and connectors therefor, and more particularly to a ground adapted to be buried in the earth, such as beneath a pole, and to a connector adapted to be utilized in connection with the ground of this invention, or with other types of grounds. The present application is a continuation in part of my copending application (now abandoned) Serial No. 757,361, filed June 27, 1947, for "Electrical Grounding Device."

One of the early types of grounds is a rod, driven for a suitable depth into the earth, and used in conjunction with lightning rods, at telegraph and telephone poles, substations, transformers, and other electrical installations. When an electrical ground is to be made in connection with a pole, such as to ground the circuits for safety, the length of rod required is usually much greater than the depth of hole dug to receive the butt end of the pole, and it is thus necessary, when using a single rod, to drive the rod farther down into the earth. When rocky earth is encountered, the difficulty in driving such a rod is often insurmountable. Also, for other installations, to provide an adequate contact area with the earth, a single rod is often required to be unduly long, or a large number of rods must be driven and tied together in multiple. A number of shorter rods requires an undue weight of metal, as well as producing complication in adequately connecting the rods to a ground wire or the like.

Another type of ground for a pole, particularly a transmission line pole, is a circular butt plate, which is nailed or attached to the bottom of the pole, prior to its being placed in the hole in the earth dug for the same. A wire or connector extends from the butt plate up the side of the pole, and is usually nailed or otherwise attached to the pole. However, only one side of a butt plate is in contact with the earth, the effective contact area of a butt plate thus being limited.

Among the objects of this invention are to provide a novel ground for electrical equipment or the like; to provide such a ground which can be placed in a hole or other area of limited extent; to provide such a ground which will provide an effective contact area greater than the cross sectional area of the space occupied by the ground; to provide a ground which is particularly adapted to be placed in holes dug for poles, but which may also be used in other places; to provide a ground which can be made in various forms, including a ground particularly useful for

2

high frequency electrical equipment, such as radio or television equipment; to provide a novel connector for a ground; to provide such a connector which is particularly adapted to be installed on the ground of this invention; to provide such a connector which insures direct contact of a ground wire with the ground; to provide such a connector which will reduce the total number of connections, particularly intermediate connections; to provide such a connector which will accommodate wires of different diameter; to provide such a connector which need not be taken apart, but only loosened, for attachment of a ground wire or the like; and to provide such a ground and connector, each of which is sturdy in construction and will withstand considerable abuse, yet may be manufactured readily and relatively inexpensively.

Additional objects of this invention, and the novel features thereof, will become evident from the description which follows, taken in connection with the accompanying drawings, in which:

Fig. 1 is a three-dimensional view of a ground constructed in accordance with this invention; Fig. 2 is a vertical section taken through the earth at a pole hole, illustrating a convenient installation of the ground of Fig. 1;

Fig. 3 is a top plan view of the lower portion of a modified form of the ground of Fig. 1, particularly adapted for use in grounding high frequency electrical equipment;

Fig. 4 is an enlarged, fragmentary, transverse section, looking downwardly along the line 4—4 of Fig. 1;

Fig. 5 is an enlarged top plan view of a ground connector constructed in accordance with this invention, taken at the upper end of the ground of Fig. 1;

Fig. 6 is a similarly enlarged, front elevation of the connector of Fig. 5 and an adjacent portion of a ground strap; and

Fig. 7 is an exploded, perspective view of the parts of the connector of Figs. 5 and 6, the adjacent portion of the ground strap, and a portion of the ground wire to be connected thereto.

As shown in Figs. 1 and 2, one form of the ground and connector of this invention may include a ground G which, instead of being attached to the butt end of a pole P, is placed beneath the pole in the hole 10, dug for the pole in the earth E. The ground G is provided with connecting means, such as a flat bar 11, which extends upwardly in the hole 10 and to the upper end of which a ground wire 12 may be connected, as by a connector C, the latter also being

constructed in accordance with this invention. The ground G includes an electrically conductive strip 13 which is disposed on edge in the lower end of the hole 10, and extends laterally from bar 11. Strip 13 is formed of a suitable metal such as copper, preferably being made from commercial bar, strap, plate or sheet stock, depending on the size, width and thickness required. The strip 13 may be circular, helical, or other desired shape as long as it is on edge, although in the preferred form it is generally annular and is provided with lateral configurations, such as a series of equally spaced, outwardly extending portions, all but one preferably being triangularly shaped and having outer apices 14 and inner points 15, each of which may be rounded. Both the outer apices 14 and inner points 15 may be disposed in a circle, the outer circle having a suitable diameter, usually slightly greater than that of the pole P, but less than that of the hole 10. One of the laterally extending portions may be generally rectangularly shaped, such as having sides 16 and lapped ends 17, which conveniently comprise the ends of the strip 13. As used herein, the term "triangularly shaped" portions does not mean that these portions form a complete triangle, but may comprise only two sides of a triangle, while the term "rectangularly shaped" does not require the portion to form a complete rectangle, but may comprise only three sides thereof, some of which may slope slightly, somewhat in the nature of the inclined sides of a trapezoid. Also, the extending portions may have any other desired shape.

The vertical connecting bar 11, as in Fig. 4, may be placed between the lapped ends 17 of the strip 13, for connection with the strip 13 and also to place bar 11 in a tangential position, in which it interferes least with the position of pole P in hole 10, as during placement thereof. As will be evident, the bar 11 thus extends in the same direction as the axis of the annulus of strip 13, which is also the axis of the circles of points 14 and 15, respectively. The lapped ends 17 and the bar 11 may be connected together in a suitable manner, as by a rivet 18, or a number of rivets, while solder 19 may be run around the joint and also to any desired extent between the ends 17 and bar 11, to restrain access of ground water or moisture to the engaging surfaces of the strip 13 and bar 11. The bar 11 and strip ends 17 may also be welded or brazed together.

The ground G' of Fig. 3 may be provided with a short circuiting wire or rod 21, which conveniently extends from a point adjacent rivet 18 to the apex 14 of the oppositely disposed, generally triangularly shaped, laterally extending portion. The ground G' is otherwise constructed in a manner similar to the ground G, and is particularly adapted to be utilized in grounding equipment, such as used in radio or television work, in which relatively high frequency currents are employed. The effect of certain high frequency currents, when passing around a generally circular path, apparently is to cause the generation of an harmonic or other variation of the frequency, which tends to pass back up through the bar 11 to the radio or television circuit, as an interference wave. The wire or rod 21 divides this path into three components, one of unequal distance, rather than two paths of the same distance, thereby reducing the possibility of setting up interference waves.

As will be evident from Fig. 3, the ground G is generally star-shaped, the triangularly shaped

extending portions being formed as the sides of equilateral triangles, with the adjacent sides which meet at an inner point 15 forming an angle which may vary with the diameter, one side being bent through 107° for a 10 inch diameter outer circle having seven triangular extending portions, as shown. However, the extending portions need not form equilateral triangles, nor need the side of each be a straight line, since various other shapes and configurations may be utilized, although a generally triangular shape is relatively easily formed, since a strip sufficient in length may be bent at successive points, to form the exterior angle at an apex 14, then the next inner point 15, and so on. The angle between the sides 16 of the generally trapezoidal or rectangular shaped extending portion and the adjacent triangular portion will usually differ slightly from the angle between adjacent triangular portions, while the extent of the lapped ends 17 of the strip is preferably substantially equal to the width of the connecting bar 11, although even these dimensions may vary. However, as indicated previously, advantages are obtained in so disposing the lapped ends 17 that the connecting bar 11 will extend tangentially, since in that position it interferes least with the placement of the pole P in the hole 10 and the connection of the ground wire thereto.

As shown in Figs. 5 to 7, inclusive, the connector C, constructed in accordance with this invention, may include a rear block 24 and a front block 25, each provided with a hole 26, while the upper end of the bar 11 is also provided with a corresponding hole 26, for passage of a bolt 27 having a lock washer 28 and a nut 29. The rear block 24 preferably is slightly lesser in width than the bar 11, so that the edges 30 of the upper end of the bar may be bent, as in Figs. 5 and 7, to overlap the edges of the rear block. Also, the front block 25 has a vertical groove 31 and the upper end of the bar 11 is stamped or otherwise formed to provide a cooperating groove 32, so that the ground wire 12 may be inserted between the grooves 31 and 32, and clamped securely against the bar 11. The rear block 24 is also preferably provided with a groove 34, adapted to receive the rearwardly extending bulge 35 formed when groove 32 is made in bar 11, while a pair of indentations 33 are crimped or peened in edges 30 when the connector C is installed, the indentations 33 extending into the rear block 24. The grooves 31 and 32 are preferably arcuate in shape, and the front block 25 is preferably made of thicker material than the bar 11, so that when the clamping bolt 27 is tightened, the wire will be compressed into the strap groove 31, thereby forming an extended area of contact, providing a good electrical connection. The rear block 24 is also preferably formed of thicker material than the bar 11, so as to back up the bar 11 and also permit a relatively heavy clamping pressure to be exerted against the ground wire 12. While blocks 24 and 25 are preferably made of thicker material than bar 11, they are preferably made of the same material, so that expansion or contraction due to temperature changes is identical, thereby insuring a positive and tight connection at all times.

As will be evident, when assembled for shipping, the bolt 27 may be tightened, as in Fig. 5, to hold the connector C securely on the end of bar 11. When the ground wire 12 is to be connected therewith, it is necessary only to loosen bolt 27 slightly, i. e. a sufficient distance to per-

mit the wire 12 to be inserted in the grooves 31 and 32, after which the bolt 27 is tightened, to insure a firm, sound connection. As will also be evident, the rear block 24, by virtue of its groove 34 and the overlapping edges 30 and indentations 33 of bar 11, does not tend to move from its position. Furthermore, it is unnecessary to remove any part of the connector C, and when wire 12 is inserted in grooves 31 and 33, the front block 25 is automatically aligned, so that the connector C has no tendency to require re-alignment or re-adjustment of any part in order to connect the ground wire thereto.

In installing the ground of this invention, in connection with a pole P, the hole 10 for the pole is preferably made an inch or two deeper than otherwise. The ground G is placed in the bottom of the hole, and in soft earth, merely pressed in by a tamp or other suitable device. When in rocky ground, relatively finely divided earth is preferably tamped in around the strip 13. Also, in very dry earth, the finely divided earth may be treated with salt, blue vitriol, or other suitable material to insure that moisture will be retained in dry weather. The vertical or "on edge" position of the strip 13 is of considerable advantage, since a better contact can be provided, than if the ground were being placed from above on earth previously placed in the hole, as in the case of a butt pole ground, which is nailed to the bottom of the pole, since there is no assurance of contact over the entire area of the plate on the bottom of the pole. The lower end of the pole need not be spaced above the bottom of hole 10 to the extent indicated in Fig. 2, although such spacing is permissible. It is not objectionable to drop the pole directly onto the ground G, since with some earth around it, there is no possibility of damage or distortion. In fact, there is little possibility of damage or distortion when there is no earth around the ground G, since in compression tests, an 8 inch diameter ground constructed in accordance with this invention, formed of 1 inch wide strip copper .0625 inch thick, withstood a compression load of 20,000 pounds, which is many times the weight of the heaviest pole which might be used.

The ground of this invention may also be installed apart from a pole, as in a hole dug for the purpose, to provide a ground for substation or other equipment, or at a radio or television station. Such a hole need not be as deep as that required for a pole, although a depth to or below the frost line is preferred, the length of bar 11 being correspondingly less. Also, a number of grounds may be buried in the same or separate holes. Such multiple grounds may be connected together in a suitable manner, the connector C also being adapted to be used in connecting a ground wire to a conductor, such as a strap leading from bus bars, transformers, or other electrical equipment.

The preferred shape of the ground G of the present invention also provides a greater contact area, in proportion to the weight of material, than other accepted pole grounds. For instance, in the case of a commercial ground constructed as shown in Fig. 1 and having an exterior diameter of 8 inches, the strip 13 is 43 inches long prior to bending, one inch high, and about .0625 inch thick. Allowing for one inch overlap, the contact area, on both sides of the strip, is about 84 square inches. A circular metal plate, adapted to be nailed to the bottom of the pole, which is 8 inches in diameter and has a thickness

of .0625 inch, will have only about 50.5 square inches of contact area, and yet has approximately 17% greater weight, i. e. requires 17% more material. When the connecting means or conductor 11 is considered, the relative contact area appears additionally more favorably. Thus, with a bar 11 having a length of 66 inches and a width of 1 inch, a customary size, 132 square inches of contact area is added to the ground of this invention, but only 66 square inches to a pole butt ground, since the conductor is normally nailed to the pole, and only one side contacts the earth. In some instances, the ground wire passes down the pole, and is connected directly to the plate nailed to the bottom of the pole, but this creates a further disparity between the effective contact area of a pole butt ground so installed and the ground of this invention.

The common type of ground rod also has less total contact area and requires a greater weight of material. For instance, a $\frac{5}{8}$ inch diameter ground rod which is 8 feet long, a size commonly used, has an exterior area of about 188 square inches, whereas an 8 inch outside diameter ground constructed in accordance with this invention, formed of strip 1 inch wide, provided with a 66 inch connecting bar, has a total effective earth contact area of 216 square inches. In addition, the $\frac{5}{8}$ inch by 8 foot ground rod weighs over four times as much as the above 8 inch diameter ground of this invention.

The connector of this invention contributes not only to the effectiveness of the ground, but also may be utilized with other types of grounds. The effective clamping of the ground wire or connecting wire, to a conductor or connecting bar, solves a problem of no small moment. A direct contact of the wire with the bar, and particularly in a groove into which the wire is pressed by considerable clamping pressure, insures that an adequate electrical connection will be made. As indicated previously, it is unnecessary to take the connector apart and the front block is automatically aligned by inserting the wire into the receiving grooves.

Little difficulty in manufacturing will be found, since the strip 13 is readily bent to shape, while the bar 11 is readily attached thereto. The connector C is also readily made and applied to the ground. The end of the connecting bar 11, or any other conductor, is readily formed to provide the wire receiving groove 32 and bent edges 30, which overlap the rear block. Also, the front and rear blocks of the connector are each readily formed to provide merely a longitudinal groove and a bolt hole therein. As will be evident, the connector is adapted to receive wires of various diameters, since the wire is pressed into the material of the connecting strap, normally copper, which is more readily deformed than the thicker clamping blocks, while the wire itself will also tend to be flattened if slightly smaller in diameter than the receiving grooves.

The ground of this invention has received commercial acceptance. At the present time, there are only three types of grounds which are approved by the Rural Electrification Administration for use on REA lines. One of these is the conventional driven rod; another is the pole butt ground, of which several types are approved; and the third is the "Groundmaster Starex," constructed in accordance with the present invention. Approval of the latter is contained in the notice which appeared on page 55 of the August 1948 issue of "Rural Electrification Maga-

zine," under the heading "Additions to approved materials list," in the following language:

"The committee unanimously accepted the following Starex grounds for use as pole grounds:

Catalog No.	Size, inches
GM68166	8
GM610166	10
GM612166	12

It is significant to note that of quite a number of materials approved in that issue (of which the "Starex" was the only pole ground), the ground of the present invention was the only one indicated as having been approved unanimously by the committee. The commercially manufactured grounds, constructed in accordance with this invention, also meet the requirements of the U. S. Bureau of Standards, the Public Service Commission of Illinois, and other authoritative or regulating bodies. Such approval, coupled with the novelty and uniqueness of the ground of the present invention, is believed indicative of a high degree of invention in the development of the present ground and connector therefor.

From the foregoing, it will be evident that the ground and connector of this invention fulfill to a marked degree the requirements and objects hereinbefore set forth. Also, although certain specific embodiments of the ground and connector have been disclosed herein, it will be evident that other embodiments may exist, and that various other changes may be made, all without departing from the spirit and scope of this invention.

What is claimed is:

1. A ground for electrical equipment, comprising an electrically conductive strip of uniform width but on edge and having a series of outwardly extending portions, one of said portions being rectangularly shaped with slightly flaring

sides and the ends of said strip being lapped over to form the outer side of said rectangular portion, and the remainder of said portions being triangularly shaped with straight sides and rounded inner and outer points, the said triangular portions being contiguous to each other and the said outer points and inner points being disposed in respective circles; an electrically conductive bar at its lower end disposed between said lapped strip ends and extending upwardly therefrom; and a rivet extending through said lapped ends and thereby attaching said bar and said lapped ends together.

2. A ground for electrical equipment, as defined in claim 1, including a wire extending from said rectangular portion adjacent said bar across to the outer point of a triangular portion opposite thereto.
